UNITED STATES PATENT OFFICE

CARL E. EKLIND AND WILLIAM W. DARROW, OF CHICAGO, ILLINOIS, ASSIGNEES TO
CAMEL COMPANY, OF CHICAGO, ILLINOIS, A CORPORATION OF ILLINOIS

CAR DOOR

Application filed January 3, 1927. Serial No. 158,497.

This invention relates to a car door and concerns itself primarily with means for repairing or replacing parts of the door which have become deteriorated.

5 Due to defects in manufacture, a great many car doors have been constructed to afford water pockets at the lower portion thereof, in which rainwater and the like would gather and cause deterioration of the bottom 10 portion of the door. This invention provides means for repairing such doors whereby it becomes unnecessary to discard the same completely.

The invention comprises the novel structures and combination of parts hereinafter described and more particularly pointed out and defined in the appended claims.

In the accompanying drawings which illustrate a preferred embodiment of this invention and in which similar reference numerals refer to similar features in the different views:

On the drawings:

Figure 1 is a fragmentary side elevational view of a house car having a door embodying this invention.

Figure 2 is an enlarged sectional view taken upon the line II-II of Figure 1.

Figure 3 is an enlarged broken sectional view taken upon the line III-III of Figure 1.

Figure 4 is an enlarged broken sectional view taken upon the line IV-IV of Figure 1.

Figure 5 is a fragmentary elevational view 25 of a modification of the invention.

As shown on the drawings:

In order to explain this invention there is shown a side of a railway car having a sliding door 1 which is supported by means of rollers 2 upon an upper or horizontal track 3. The door 1 was originally of wood, the lower part thereof having become deteriorated as previously set forth and having been removed and replaced by a corrugated sheet metal panel 4. The door has a flanged weather strip 13 along its front edge and a flanged weather strip 14 along its rear edge for cooperating with suitable weather strips upon the car.

Obviously these sheet metal panels may be 50 formed and shipped to the various railroads

which will apply them to the deteriorated doors by sawing off the decayed part according to the width of the corrugated panel and applying the panel to the door. To this end the corrugated panel is provided with an upper seat 5 for engaging the lower end of the remaining portion of the door and an attaching flange 6 extending from the inner edge of the seat for attachment to the lower interior margin of the door. The panel 4 is provided with lateral and inwardly directed flanges 15 (Fig. 4) which lie against the weather strips 13 and 14.

Where the door to be repaired is suspended on rollers the sheet metal panel 4 is provided with a depending angle 7 at the lower edge thereof. This depending angle 7 is provided with the usual cams 8 cooperating with curved abutments 9 on the brackets 10 beneath the door for moving the door in a closed position. However, in case the door to be repaired is supported upon the lower track, the sheet metal panel 4 may be provided with suitable roller supports 11 as shown in Figure 5 in which suitable rollers 12 may be journaled.

The resulting structure produces a composite door consisting of a wooden panel and a metal panel which is designed to last the life of the car. It will be particularly noted that the seat 5 is formed by a transverse bend at the upper end of the corrugated sheet and the attaching flange 6 is upon the interior of the door. Consequently water pockets or the like are obviated at the lower edge of the wooden panel and the water may easily drain down the metal panel.

It will be appreciated that this invention is designed to effect a great saving to the railroads since it is but a simple matter to saw off the decayed lower end of the door and apply the corrugated metal panel thereto.

We are aware that many changes may be made and numerous details of construction may be varied through a wide range without departing from the principles of this invention and we, therefore, do not propose limiting the patent granted thereon, otherwise than necessitated by the prior art.

We claim as our invention:

1. In a car door, an upper wooden portion,

- angular weather strips upon the lateral margins of said wooden portion and extending therebelow; and a lower metal panel having a horizontal seat for supporting the lower edge of the upper portion and having lateral flanges abutting said weather strips, said seat terminating in an interior flange extending adjacent the interior surface of said wooden portion.
10. 2. A salvaged car door comprising an upper wooden portion, weather strips attached to the lateral margins of said wooden portion and extending therebelow and having transverse inwardly directed portions in combination with a corrugated metal panel having an upper right angled seat opening outwardly for receiving and supporting the lower edge of said wooden portion and having lateral flanges abutting the inwardly directed portions of said weather strips and means for securing said metal panel to said wooden portion.
15. 3. In a salvaged car door, an upper wooden portion, metal weather strips upon the lateral margins thereof and having transverse inwardly directed portions extending below said wooden portions, and a corrugated metal panel having an upper corrugation flattened to provide a horizontal seat for
20. 30 receiving and supporting the wooden portion; and an interior flange attached to said wooden portion, said metal panel having parts abutting the inwardly directed portions of said weather strips.
35. 4. In a car door, an upper wooden portion, weather strips upon the lateral margins of said wooden portion and extending therebelow and a lower metal panel having a horizontal seat for supporting the lower edge of the upper panel and having its lateral edges abutting said weather strips, said horizontal seat terminating in an interior flange extending adjacent the interior surface of said wooden portion.
45. In testimony whereof, we have hereunto subscribed our names.

CARL E. EKLIND.

WILLIAM W. DARROW.
